COMBINED ELECTRIC COOKER AND BUN TOASTER

Gilbert Courshon, Chicago, Ill.

Application May 20, 1955, Serial No. 36,143

Term of patent 7 years

(Cl. D81—10)

FIG. 1

FIG. 3

Fig. 1 is a front elevation of a combined electric cooker and bun toaster, showing my new design;

Fig. 2 is a top plan view; and

Fig. 3 is an elevation from the right-hand side of Fig. 1.

I claim:

The ornamental design for a combined electric cooker and bun toaster, as shown.
